FIG. 6

Inventor:
George Fraser

By Sheridan J. Sheridan
Atty's

UNITED STATES PATENT OFFICE.

GEORGE FRASER, OF TOPEKA, KANSAS.

GREASE PLUG.

Application filed July 28, 1923. Serial No. 654,347.

To all whom it may concern:

Be it known that I, GEORGE FRASER, a citizen of the United States, residing at Topeka, in the county of Shawnee and State of Kansas, have invented certain new and useful Improvements in Grease Plugs, of which the following is a specification.

This invention relates to improvements in grease cups and more particularly to the 10 plugs employed therein for compressing or feeding the grease therefrom.

One object of the invention is to provide a plug of the character described having self contained means for holding it against accidental displacement in any of its various 15 positions of adjustment. Other objects and advantages of the invention will be apparent from the following description taken in connection with the accompanying drawings, 20 wherein one form of the invention is illustrated.

In the drawings—

Fig. 1 is a sectional view taken through a grease cup, showing a plug constructed in 25 accordance with the present invention, operatively positioned therein;

Fig. 2 is a side elevation of the plug;

Fig. 3 is a top plan view of the plug showing the parts in the position they 30 occupy when the plug is in position in the cup;

Fig. 4 is a top plan view of the plug showing the parts in the position they occupy when the plug is removed from the cup;

Fig. 5 is a bottom plan view of the plug; 35 and

Fig. 6 is a sectional view taken on the line 6—6 of Fig. 3.

Referring more in detail to the drawings, 40 the grease cup is designated 10 and may be of any of the well known constructions, the same being internally screw-threaded as at 11. The plug is designated in its entirety by reference character 12, and is provided 45 with a cut out portion 13, which extends downwardly from the top of the plug to a plane slightly below the center transverse axis, the base 14 of the plug being integral and cylindrical in shape, and of a diameter 50 corresponding to the interior diameter of the cup.

Pivottally mounted upon the base portion 14, of the plug, and substantially filling the 55 cut out portion 13 thereof, is a movable section 15. The pivot pin bears reference character 16 and may be of any suitable

form such as a rivet, or the like. The adjacent faces of the main portion of the plug and the movable section 15 thereof are provided with two pairs of complementary recesses 17 and 18, the former, when the plug is assembled, forming a triangular socket 19 adapted to receive the end of a wrench or the like, for operating the plug.

The complementary recesses 18 receive the 60 opposite ends of a coiled spring 20, which is interposed between the main part of the plug and the movable section 15 thereof, this spring normally tending to move the section 15 on its pivot, causing the end of

said section against which the spring bears to protrude beyond the normal circumference of the plug, as shown more clearly in 65 Fig. 4. In other words, the plug is expanded at this point, causing the screw threads thereof to bind against the sides of the cup by reason of which the plug is held against accidental displacement. As shown in the 70 drawings, the plug is screw threaded from end to end, for engagement with the screw threads of the cup, the screw threads on the curved face of the section 15 being a continuation of the screw threads on the main portion of the plug, so that the combined 75 assembly may be screwed into and out of the cup in the same manner as with plugs of ordinary construction. The recess 17 in the main portion of the plug extends downwardly into the base portion 14 and the recess 17 of the movable section 15 of the plug extends completely through the latter from 80 top to bottom and communicates at its lower end with the socket continuation formed in 85 said base 14. From this it will be observed that the bottom of the socket 19 is fixed, the 90 sides thereof being relatively immovable, while the contrary is true of the portion of the socket 19 which extends above the base 14 of the plug, this portion of the socket being formed by the complementary recesses 95 90

17. This arrangement is preferably such that the recess 17 in the movable section 15 coincides with the corresponding portion of the socket in the base 14 when said section 100 occupies the position shown in Fig. 3. This being true, the long side of the recess 17 in the movable section 15 assumes a position slightly offset inwardly of the corresponding side of the socket in the base 14 when the section 15 is in the position shown in Fig. 4.

105 In this manner undue binding of the parts is prevented during use of the wrench in 110

applying, removing or adjusting the plug. In other words, the plug may be operated in either direction with but one operation, the same as with the solid plug now in common use.

It will be obvious to those skilled in the art that the present improvements are susceptible of various changes and modifications without departing from the spirit of the invention and it is not, therefore, desired to limit or restrict the same to the particular form or arrangement of parts herein illustrated, except where limitations appear in the appended claims.

15 What I claim is—

1. A grease cup plug comprising complementary sections forming an externally screw-threaded plug having a socket therein to be engaged by a wrench, or the like, said sections being relatively movable, one thereof having a portion underlying the other, and means normally tending to expand said sections, said socket being formed by complementary recesses in said sections, the recess in the section having the underlying portion extending downwardly into said portion and forming a continuation of said socket.

2. In combination with a threaded grease cup, a plug engageable therewith, said plug comprising a threaded body portion, recessed to accommodate an operating member, a segmental shoulder portion projecting

upwardly from said body portion, a complementary portion pivotally mounted upon said body portion and defining with said shoulder portion the recess in said plug, means co-acting with said shoulder and complementary portions to displace the latter relative to the underlying body portion about its pivotal mounting.

3. A grease plug comprising an externally threaded body, said body being provided with a recess for engagement by a tool or the like, and being cut away adjacent to said recess, a complementary member pivotally mounted on said body, and located in said cut away portion, and means to normally displace said complementary member with respect to the adjacent portion of said body member.

4. A grease plug externally threaded and socketed to accommodate an operating member, said plug having a projecting segmental shoulder, a co-acting complementary member adjacent thereto, and yielding means to displace said complementary member relative to said shoulder to frictionally contact a surrounding cap or the like, said shoulder and complementary member being recessed to continue said socket of said plug.

In testimony whereof, I have subscribed my name.

GEORGE FRASER.
